UNITED STATES PATENT OFFICE

AXEL HOLMSTROM, OF MONTE CARLO, MONACO

PROPELLER OR TURBINE FOR WATER, AIR, AND GASES

Application filed April 8, 1929, Serial No. 353,407, and in Germany October 12, 1928.

My invention relates to water craft, air craft or the like and to a propeller therefor.

One purpose of my invention is to provide a propeller of the type indicated with a stream-line core along its axis in order to give the fluid operated upon by the propeller stream-line approach into the propeller and stream-line rearward delivery away from the propeller.

10 A further purpose is to decrease the blade friction of a propeller by giving the blade a fish-scale surface, preferably delivering air through the propeller to the scale edges.

15 A further purpose is to lessen the friction of a water craft by giving its submerged portion a fish-scale surface and by discharging air to the edges of the scales.

20 A further purpose is to guide the fluid discharge of a propeller inwardly toward the propeller axis along streamlines by means of a tubular guide around the outside of the propeller, preferably placing a cooperating guide as a streamline core in the propeller axis extending rearwardly from the propeller, the outer tubular guide providing streamline inward flow to the core.

Further purposes will appear in the specification and in the claims.

Figure 1 is a fragmentary view showing 30 a propeller for a motor boat or the like, said propeller embodying a desirable form of one feature of my invention.

Figure 2 is a perspective view to considerable extent diagrammatic indicating a somewhat different form of propeller from that of Figure 1.

Figure 3 is a fragmentary end elevation of a desirable form of propeller embodying some features of my invention.

40 Figures 4, 5 and 6 are sections of different desirable streamline forms for the propeller blade, each form presenting a fish-scale surface to the reacting fluid.

Figure 7 is a fragmentary horizontal view 5 through the side wall of a boat beneath the water surface showing a desirable fish scale structure upon the outside of the submerged surface of a boat.

50 Figures 8, 9 and 10 may each be considered as a side elevation of structure shown in Fig-

ure 7 but illustrating different forms of plate laminations, Figures 9 and 10 looking in reverse direction from Figures 7 and 8.

Like numerals refer to like parts in all figures. 55

It is well known that a body of a stream-line conformation is particularly adapted for motion through a fluid medium, either liquid or gaseous, because the forward motion of such a body causes a compression of the medium which in turn tends to expand and by so doing, presses the body forward.

It is evident that the reaction of the expansion of the compressed medium on such bodies will be greater, the higher the compression is and the more it can be concentrated. The compressed medium would, so to speak, act as an accumulator and press the body forward like a piston.

This invention relates to a stream-line body 70 on which specially formed propeller blades are arranged in such a way as to shovel or draw the medium from ahead, press it together and drive it towards the rear part of the body in the form of a compressed medium column. Hereby also the center part of the medium, for instance water, will be utilized and not only, as heretofore, the outer part of the medium column. Thus all of the medium within reach of the propeller action, also the 75 center part of the medium column, will be taken in by the propeller blades and driven rearwards as a compressed medium column. The effect of the propeller can be still further increased through a special construction of 80 the surface of the propeller blades.

It is well known that the scales of a fish tend to reduce the friction in water, because of the very low adhesion of water to the scales, and therefore facilitate the swimming 85 of the fish.

Furthermore the smooth scales overlap each other, giving the surface a step-like formation. By motion forward an air-filled space is formed back of each of these steps 95 which tends to reduce the resistance of the fish at the same time as the pressure of the medium column on the rear part of the body is taken up by these steps.

These facts are utilized in the new pro- 100

peller by giving the surfaces of the propeller body and propeller blades a step formation and a series of openings through which air can be released.

5 The propeller body *a* has a streamline formation, the front part of the body, seen from the side, showing elliptical lines at *b* which run together to a point *c*. Rearwardly at *d* the lines run slowly together, giving 10 the rear part of the body a pyramidal or conical or preferably conoidal form with sufficient surface to take up the pressure of the water the convexity of longitudinal sections through the axis is quite desirable 15 to secure the stream line effect sought. The front part of the body carries the propeller blades *e* which serve a double purpose.

The blades, when revolving, not only drive the body forward, but also at the same time 20 draw the water to the propeller, press it between the blades and drive it backwards, highly compressed.

To prevent expansion of the compressed medium away from the center of the propeller, "girdle-rings" *f* are arranged.

When the propeller revolves, its blades draw the water to the propeller as well from the extreme ends of the blades as from the center of the medium column, as shown by 30 the streamlines, and rearwardly of the blade press it inward against the propeller body *d*.

Thus the water is drawn in by the propeller blades as a compressed water column from the center of the propeller to the extreme ends of the blades.

This water column, on its way from the front part of the stream-line body to the widest section of the same, is naturally being more and more compressed, until after passing 40 this section it again expands and reacting on the rearward sloping part *d* of the body, presses the body evenly and forcefully forward with a pressure proportionate to the expansion. The rings *f* prevent expansion

45 outwardly opposite the propellers and help to determine the direction of rearward flow of the column.

Trials have shown that higher speeds than heretofore possible can be obtained with a 50 propeller of this type.

To further improve the action of the propeller, its blades are given scale-formed surfaces, as shown in Figures 3 to 9. The surfaces are not smooth but provided with steps 55 *h* of suitable formation, these steps having small openings on the side.

Figures 3 to 9 show a few of the many 60 different forms of such steps or scales. This arrangement not only prevents the medium, for instance water, from sticking to the revolving blades because of the continuous interruptions by the steps, but back of each step air is released through the openings *i*, this air also assisting the movement of the 65 blades.

Thus the blades move through the medium, covered with a layer of air which tends to reduce the resistance of the propeller at the same time as the many small bubbles of compressed air back of the steps *h* press on these steps and accordingly assist the movement of the propeller.

In the propeller shown in Figure 1 the rotor element includes an outer guide or girdle ring *f*, the propeller blades *e*, a hollow forward portion of the core *b*, a gear 15 fastened to the core member and a tubular shaft 16, all of these elements turning as a unit.

The rotor shaft 16 is rigidly fastened in the hollow forward portion of the core and is mounted in bearings 17 and 18 inside the hollow rearward portion *d* of the core which also gives a bearing support to the lower end of a drive shaft 19 carrying a gear 20 in mesh with the gear 15.

The drive shaft 19 is inside a hollow vertical arm 21 which extends downward from the bottom of the craft carrying the propeller, for example from the bottom of a motor boat, the shaft being driven by a motor inside the craft, not shown, being irrelevant to the present invention.

The vertical arm 21 is desirably angularly movable on its own axis for adaptation to use as a rudder; the rearward end of the core then being provided with fins 22 alining with the current discharging from the propeller.

In Figure 2, the core, shaft and the propeller blades are a single member rotating as a unit.

The shaft 16 projects rearwardly or forwardly through the end of the craft, for example through the stern or bow of a motor boat, into the water, and the girdle ring *f* surrounding the blades may either be separately supported from the craft or may rotate with the blades, according to preference or circumstance.

As indicated in Figures 3 to 6 the surface of the propeller is preferably provided with fish-scale steps and preferably air is delivered to the surface of the propeller at the edges of the steps *h* in any suitable way, both the step formation and the introduction of air at the step edges reducing the propeller friction.

In Figure 1 the air may be delivered through the hollow shafts 19 and 16 and intermediate perforations 23 and 24 into the hollow core member *b* and thence through perforations 27 into the interior of the individual propeller blades, to escape at the edges of the fish scale steps at the openings *i*.

Figures 3 to 6 are to a considerable extent diagrammatic and illustrate a few only of the many different forms the propeller blades may take, these views corresponding to sections perpendicular to radii at the middle of the respective blades, the direction of move-

ment of the blade corresponding to that indicated by the arrows.

Figures 7 to 9 illustrate another desirable feature of my invention, that is particularly advantageous when applied to the submerged surface of a motorboat.

I provide the outside submerged portion of a boat with what I have called a fish-scale surface in which the outer plates *h* fastened to the outside of the boat at *k* form a succession of steps similar to those of a shingle roof or to those presented by the scales of a fish.

The movement of the boat is in the direction of the arrows so that the fluid through which the boat is moving passes successively over the steps. Preferably air is delivered to the edges of the steps either from the interior of the boat into suitable compartments *v* and thence out through openings *i* or from the outside of the boat.

It will be understood that a speeding motorboat may skim the water surface in a way that causes a stream of air to pass under the boat. This air fills the spaces at the edges of the steps of the fish-scale surface and results in a lessened friction between the water and the bottom of the boat.

It will be noted that the body of my propeller is generally pear-shaped. The forward portion is preferably elliptical and the rearward portion preferably convexly conoidal.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

1. A propeller in combination with a stream-line core at the propeller axis, the front part of the core being rotatable with the propeller and the rear part fixed and a circumferential guide around the outside of the propeller.

2. In a water propeller, a blade having a fish-scale working surface, the abutment edges of the scales being directed circumferentially rearwardly of the propeller travel to permit the water to slide over the scale surface without engaging the abutment faces thereof and means for delivering and liberating air on the said surface at the edges of the scales.

3. A craft for travelling through fluid, said craft having a fish-scale surface presented to the fluid through which it travels with the abutment edges of the fish-scale surface directed rearwardly of the line of travel and

means for delivering air to the edges of the individual scales.

4. A body adapted to be forced through water and having a stepped surface for presentation to the water with the steps directed rearwardly with respect to the direction of travel of the body and connections for delivering air through the body to release it at the surface adjacent the edges of the steps.

5. A propeller including a stream-line core at the propeller axis, means for rotating the front part of the core as a part of the propeller, means for rearwardly supporting the rear part of the core in line with the rotatable core part, a succession of fish-scale steps on the working face of the propeller, said step surfaces facing rearwardly with respect to the direction of their circumferential travel to permit the fluid operated upon by the impeller to slide more easily past the steps and means for delivering air to the working faces of the impeller along the step faces.

6. In a propeller, hollow propeller blades having circumferentially rearwardly directed steps on the working surface thereof and openings at the step faces into the hollow interior, and a hollow propeller shaft in conduit connection with the hollow of the blades and with a source of air supply for releasing air at the step surfaces.

7. In a propeller for use in water, a bearing having a fixed support, a hollow shaft mounted in the bearing, a gear thereon, a second gear meshing with the first, a hollow shaft for the second gear, a second bearing having a supporting connection with the first bearing and hollow propeller blades supported by the second hollow shaft whereby air admitted under pressure into the first hollow shaft may be released at the surfaces of the blades.
